UNITED STATES PATENT OFFICE.

HARRY G. WESTGATE, OF UNION CENTER, NEW YORK.

NON-REFILLABLE BOTTLE.

1,032,259.

Specification of Letters Patent.

Patented July 9, 1912.

Application filed April 11, 1911. Serial No. 620,352.

To all whom it may concern:

Be it known that I, HARRY G. WESTGATE, citizen of the United States, residing at Union Center, in the county of Broome and 5 State of New York, have invented new and useful Improvements in Non-Refillable Bottles, of which the following is a specification.

My present invention pertains to bottles 10 constructed with a view to preventing fraudulent refilling thereof; and it consists in the peculiar and advantageous non-refillable bottle hereinafter described and definitely claimed.

15 In the drawings accompanying and forming part of this specification: Figure 1 is a view, partly in diametrical section and partly in elevation of so much of a bottle as is necessary to illustrate the best practical embodiment of my invention that I have as yet devised. Figs. 2 and 3 are horizontal sections taken in the planes indicated by the lines 2—2 and 3—3, respectively, of Fig. 1, looking downward. Fig. 4 is a detail inverted plan illustrative of the element in which the valve seat is formed.

Similar letters of reference designate corresponding parts in all of the views of the drawings.

30 The body A of the bottle is provided with a short upstanding tubular portion a, internally threaded at b and chambered at c; and the said portion a serves in combination with a comparatively large tubular section 35 B to form the neck of the bottle, said tubular section B being reduced and externally threaded at d to engage the thread b of the portion a, and glass or other suitable cement e being placed in the chamber c. In this 40 connection I would say that I prefer to dip the threaded portion d of the section B in a body of glass cement, and then screw the said threaded portion d into the portion a of body A, whereupon the glass cement will 45 occupy the mentioned chamber c and by reason thereof will be prevented from leaking into the body A.

The tubular neck section B is provided at 50 its lower end with an interior thread f, and above said thread it has an upwardly tapered bore g, while at the upper end of the said taper bore the section is internally enlarged, as indicated by h, to form a support hereinafter referred to. The portion of the 55 section above the support h is preferably shaped as shown to receive an ordinary cork

stepper or any other stopper that I have deemed it unnecessary to illustrate.

In the lower interiorly threaded end of the neck section B, I arrange an exteriorly 60 threaded body C which is apertured at i and chambered at j, and in the said chamber j I suitably fix a cross-bar k. The aperture i is designed to form a seat for the vertically swinging valve D, hinged at l to the body C, and the cross-bar k is designed for the connection of a fine spring E, which is interposed between said cross-bar and the valve D, and is possessed of just enough tension to close the said valve when outflowing 65 liquid is not forcing the same outward. By reference to Fig. 1 it will be understood that nothing but a force exerted from the inside of the body A will open the valve D; also, that the bottle cannot be filled by laying it on its side, inasmuch as anything acting against the top or outer side of the valve D only serves to hold the said valve the more tightly to its seat.

For the purpose of precluding the introduction of an instrument to the lower portion of the neck, and the utilization of such an instrument to tamper with or hold the valve D open, I provide the peculiar and advantageous guard means illustrated. This 80 guard means comprises a threaded stem F having a head m, an upper disk G loosely arranged on the said stem and having a countersink in its upper side to receive the head m, and also having off its center a vertical aperture p, an intermediate disk H loosely arranged on the stem F and having an aperture r at a point off its center, a lower disk I also loosely arranged on the stem and having an aperture s at a point 85 off its center, a nut J threaded on the stem and disposed below the disk G to clamp the same against the head m, nuts K and L mounted on the stem and between which the disk H is clamped and held, and nuts M and N also mounted on the stem and between 90 which the disk I is clamped and held. The guard means is placed in the bore of the neck section B precedent to the connection of the said neck section, to the tubular portion a of the body, and by reason of the said bore in section B being tapered upward, and the disk G being arranged on the before-mentioned support h, and the disks H and I being of a diameter to snugly fit the 95 upwardly tapered bore, it will be manifest 100 that when the guard means is arranged as

shown in Fig. 1, said means will be strongly and rigidly fixed in the tubular section B and there will be no liability of the guard means casually moving.

5 The apertures *p*, *r* and *s* of the several disks G, H and I are arranged in staggered relation to further the purpose ascribed to the guard means as a whole, and here I would direct attention to an important feature 10 of my invention, namely—the adaptability of the disks G, H and I to be readily adjusted on the stem and fixed in various positions thereon, so as to vary the relation of the apertures *p*, *r* and *s*, and so that 15 when the section B is made of opaque glass, no one but the authorized party who puts the guard means in the neck section B will be cognizant of the manner in which the disks are placed to relatively dispose the 20 apertures in the disks, which apertures are for the outward flow of liquid. The body A and the tubular section B are preferably of glass, while the remaining elements comprised in the improved construction are 25 preferably of a metal or metals suitable to the purpose.

In practice, liquid may be poured with facility from the body A and through the neck of the bottle, the valve D giving outward under the pressure of the liquid and permitting the liquid to pass the same. When, however, the outward pressure of liquid against the valve D ceases, the spring E will immediately return the valve D to 30 and hold it against its seat, and from this it follows that liquid cannot be introduced into the bottle past the valve D, no matter in what position the bottle is arranged.

Having described my invention, what I 40 claim and desire to secure by Letters-Patent, is:

1. In a non-refillable bottle, the combina-

tion of a body, a neck section connected to the body and having a bore tapered or reduced in size upward and also having a support at the upper end of said bore, a suitably-supported outwardly opening valve intermediate the interior of the body and the interior of the said neck section, and guard means arranged in the neck section and comprising a vertical-central threaded stem, disks mounted on and rotatable about said stem and having vertical apertures arranged off their centers; one of the said disks resting on the said support in the neck 55 section, and the other disk resting in the taper bore and being held against upward movement by said taper, and the disks being rotatable relative to each other whereby the relative arrangement of the apertures 60 can be changed, and nuts mounted on the stem and adapted when set against the disks to fix the same to the stem.

2. In a non-refillable bottle, the combination of a body, a neck section thereon and having a bore, a suitably-supported outwardly opening valve intermediate the interior of the body and the interior of the neck section, and guard means suitably supported in the neck section and comprising a 65 stem, disks mounted on the stem and spaced from each other and having apertures off their centers; one of the said disks being loose on the stem and rotatable with respect to the other whereby the relative arrangement of the apertures can be changed.

In testimony whereof I have hereunto set my hand in presence of two subscribing witnesses.

HARRY G. WESTGATE.
